(57) **CLAIM**

The ornamental design for a connection for windshield wipers, as shown and described.

DESCRIPTION

FIG. 1 is a perspective view of a connection for windshield wipers.

FIG. 2 is a left side view thereof.

FIG. 3 is a right side view thereof.

FIG. 4 is a front view thereof.

FIG. 5 is a rear view thereof.

FIG. 6 is a top plan view thereof;

FIG. 7 is a bottom plan view thereof.

In the drawings, the broken lines in FIG. 7 depict portions of the article that form no part of the claimed design.
